UNITED STATES PATENT OFFICE

2,450,606

EGG CLEANER

Edward T. Molitor, Seattle, Wash.

Application July 23, 1945, Serial No. 606,512

2 Claims. (Cl. 51—73)

1

This invention relates to egg cleaners and it has reference more particularly to means for the removing of dirt or stains from the surfaces of eggs for the purpose of enhancing their appearance and for increasing their market value.

It is the principal object of this invention to provide an egg cleaning device of the above character whereby the cleaning operation may be effectively and quickly accomplished and with a minimum loss of eggs from breakage.

It is also an object of the invention to provide an egg cleaner of the buffer type that does not require the use of any liquid cleaning agent in connection therewith, nor does it require the withdrawing of the egg from the machine for the turning or reversing of the egg in the hand in order that all of its surface might be brought against the cleaning buffer.

More specifically stated, the objects of the present invention and the advantages to be obtained thereby, reside in the provision of an egg cleaner comprising a substantially cylindrically shaped buffer with elastic or resilient abrasive equipped walls and wherein the buffer is mounted for high speed rotation, by a motor driven head that is applied within one end of the cylindrical buffer body; the other end of the buffer body being open and of such diameter that an egg, held in the hand, may be located inside the buffer, easily handled and turned in order that all of its surface may be brought against the abrasive wall.

It is also an object of this invention to provide an egg cleaning device of the character above stated wherein the buffer wall is of a resilient or elastic character, such as provided by a rubber tube, and will readily conform to the curvature of the egg when the egg is pressed against the wall.

Still further objects of the invention reside in the details of construction and combination of parts comprised in the machine and in its mode of operation, as will hereinafter be fully described.

In accomplishing these and other objects of the invention, I have provided the improved details of construction, the preferred forms of which are illustrated in the accompanying drawings wherein:

Fig. 1 is a side view of the present egg cleaning machine, but showing the cylindrical buffer in longitudinal section for better understanding.

Fig. 2 is an elevation of the machine, looking directly into the open end of the cylindrical buffer.

Fig. 3 is a sectional detail of the buffer wall in the axial direction of the buffer, showing the

2

manner in which it conforms to the curvature of the eggshell when the egg is pressed against it.

Fig. 4 is a sectional detail of the buffer wall transversely of the axial direction, illustrating the relationship of the abrasive strips that are applied thereon.

Referring more in detail to the drawings:

In its present preferred form of construction the device employs a small, electric motor 8 as the power source fixed on a base 10. This motor has its drive shaft 11 extending from one end thereof and fixedly mounted on this shaft is a head, disk or wheel 12. This wheel may be of wood, or other suitable material and it is fixed within one end of a cylindrical buffer of corresponding diameter, designated in its entirety by reference numeral 15. The buffer is horizontally disposed and is mounted coaxially of the shaft 11 and wheel 12 so that, at high rate of rotation, there will be no undue vibration or detrimental eccentric action.

The buffer 15 is composed of rubber or other suitable flexible, or elastic material; for example, a rubber tube. In its present preferred form, it is approximately six inches in diameter and four inches long and the rubber walls thereof are approximately one-sixteenth inch thick. In the use of the device, the buffer is rotated at what may be termed a high rate of speed, but this may be under control and varied to suit conditions or requirements. Axial rotation of the cylindrical buffer at high rate will cause the open outer end thereof to be somewhat diametrically expanded, and it will assume the form of a slightly tapering truncated cone as will be understood by reference to Fig. 1. Fixed to the buffer walls in the axial direction of the cylinder, and on the inside of its wall surfaces, are closely arranged strips of abrasive cloth 20 such as emery cloth. These may be cemented or otherwise fixed to the buffer walls and they are located in close parallel relationship as indicated. Between the strips of abrasive, the walls of the buffer are provided with slots or perforations 22.

Assuming that the device is so constructed and assuming that the motor has been energized and that the cylindrical buffer is being rotated at the required speed, it will be understood that the tubular or cylindrical buffer body will assume the shape shown in Fig. 1. For cleaning an egg, the egg is held in the hand, and inserted within the open end of the buffer in such manner that a side surface of the egg may be brought into contact with the abrasive material on the buffer wall.

In Figs. 1 and 2 I have indicated the manner in which the egg E may be engaged with the buffer,

and it will be understood also that if the egg is pressed against the buffer wall, the latter will flex and readily conform to the curvature of the contacted part of the egg thereby covering the maximum surface. The egg may be rotated or turned end for end in the hand without requiring that the hand be removed from the buffer. It is possible to contact any spot or an extended surface of the egg shell with the abrasive for rapid and effective cleaning.

In order to protect the operator in the event that an egg should be broken during the cleaning operation, I have applied an annular shield 23 about the open end of the buffer. This shield, for a six inch buffer, is approximately eight to ten inches in diameter, and two inches wide and is concentrically disposed about the open end of the buffer as shown in Fig. 1. It is shown as fixed to a bracket 24 that, in turn, is fixed to the base 10. Should an egg break, the fluid from the egg will be discharged centrifugally from the buffer and will be caught by the shield 23. Preferably the shield will be slightly cupped or troughed in cross section so as to retain the fluid.

As an alternative, instead of cementing abrasive strips to the buffer wall it is anticipated that rubber buffer tubes might be molded, or cast, with an abrasive contained on the inner wall surface. In any event it is not desirable that anything should be used to form the abrasive surface that will interfere with the diametrical expansion, elasticity or flexibility of the body which would interfere with its conforming readily to the curvature of the egg.

Devices of this character are relatively inexpensive yet quite effective for their intended purpose. Many more eggs can be cleaned with this machine within a given period of time than by any other machine now on the market. The particular advantage resides in the fact that the buffer is sufficiently large in diameter as not to obstruct the vision or impair handling of the egg and the egg may be cleaned in its entirety without having to withdraw the hand from the machine for turning the egg. The operator, in cleaning the egg, may use as much or as little pressure as required and may touch spots or rela-

tively large surfaces. The device is simple in construction and in operation and embodies no dangerous parts that might cause injury to an operator.

Having thus described my invention, what I claim as new therein and desire to secure by Letters Patent is:

1. An egg cleaner comprising a hollow frustro-conical body of resilient flexible material, open at its larger end and having a wall closing its smaller end, a motor having its driving shaft fixed to the said closing wall coaxially of the body and pieces of abrasive material applied to the inside surface of said body and there being openings through the body wall not covered by said pieces of material.
2. An egg cleaner comprising a hollow, substantially frustro-conical body of resilient, flexible material, a rotatably driven shaft, a head block fixed on said shaft and fixed within the smaller end of said body for its axial rotation, and a succession of narrow, closely arranged strips of flexible abrasive material secured flatly to the inside surface of said body lengthwise thereof; said body being open at its larger end and formed in its walls, between said strips, with openings therethrough.

EDWARD T. MOLITOR.
